UNITED STATES PATENT OFFICE.

VICTOR H. SEARS, OF NEW YORK, N. Y.

ARTIFICIAL TEETH.

Application filed April 9, 1927. Serial No. 182,399.

This invention relates in general to artificial teeth and more particularly to dentures including sets of artificial teeth for both the upper and the lower jaws.

Artificial teeth are known not to function efficiently in dentures, particularly dental plates, because of the instability of the artificial teeth in the mouth which makes it practically impossible for the occlusal surfaces of the teeth to cooperate in a grinding operation like that possible with natural teeth. Furthermore, great uneasiness is encountered by most wearers of dental plates in frequent slipping or rubbing on the ridges or gums or displacement of the plates when the teeth are brought together which causes soreness in the mouth as well as annoyance and difficulty in chewing food, etc.

Most artificial teeth are made in close simulation of natural teeth, and I am satisfied that the troubles above mentioned are largely due to the formation or shape of such artificial teeth made in simulation of natural teeth, particularly the last four back teeth on each side of each jaw, that is, the four molars and the four bicuspids on each jaw. The cusps and the occlusal surfaces of such teeth on the lower jaw interlock with the cusps of the teeth on the upper jaw and prevent relative movement of the plates both sidewise and forwardly and backwardly in the mouth. The consequence is that when pressure is exerted by the jaws either laterally or forwardly and backwardly, the upper or the lower or both of the plates slide relatively to the respective jaws or tilt due to the necessarily unstable mounting of the plates on the gums or ridges.

One object of my invention is to provide a new form of artificial teeth for the upper and lower jaws which have their occlusal surfaces so designed that free and easy relative lateral and back and forth movement of the dentures is permitted and interlocking of the teeth prevented, so that all forces exerted by movement of the jaws upon the plates and which might tend to cause sliding of the dentures upon the gums or ridges or tilting thereof, are so reduced, dissipated or translated as to prevent such sliding or tilting of the dentures. In other words, my invention provides teeth which make the plate or dentures more easily slidable relatively to each other than to the gums or ridges on which they are mounted.

Another object is to provide artificial teeth having a novel and improved form of occlusal surface whereby such relative sliding of the plates is permitted and also the cutting or grinding of food may be efficiently accomplished.

Other objects are to provide dentures including upper and lower plates wherein the molars or posterior teeth in one plate have grooves on their occlusal surfaces to cooperate with ridges on the occlusal surfaces of the corresponding teeth in the other plate in such a manner that the plates may freely slide upon each other back and forth longitudinally of the grooves and ridges and slide laterally transversely of said grooves and said ridges, said ridges normally fitting into said grooves when the jaws are closed; to provide such dentures wherein the sides of said grooves are formed with alternate projections and recesses with which cooperate said ridges in cutting and grinding or mashing food, and to obtain other results and advantages as are brought out in the following description.

Referring to the accompanying drawings, in which corresponding and like parts are designated throughout the several views by the same reference characters,

Figure 1 is a side elevation of dentures or plates for the upper and lower jaws embodying my invention;

Figure 2 is a perspective view of the lower denture showing in more detail the construction of the teeth embodying my invention;

Figure 3 is a fragmentary perspective view of the rear end of one side of the upper plate, looking at the same from beneath;

Figure 4 is a transverse vertical sectional view, taken on the line 4-4 of Figure 1;

Figure 5 is a composite perspective view of one of the upper anterior molars and one of the lower anterior molars, and

Figure 6 is a plan view of the rear of one side of the upper plate showing in more detail the grooves in the four molars.

While I have illustrated complete upper and lower sets of teeth, my invention is particularly directed toward improvement of the rear ends of the dentures and the bicuspid and molar teeth for the upper and lower jaws. In its broadest aspect my invention consists in forming grooves in the occlusal surfaces of the upper molar teeth which are adapted to receive ridges on the occlusal surfaces of

the lower molar teeth, the grooves and ridges extending from front to rear of the jaws and freely permitting back and forth and lateral relative movement of the upper and lower dentures. Preferably the grooves and ridges have inclined sides substantially the whole of each of which is in one plane to facilitate the relative sliding of the dentures. While I have shown the molars as separate teeth, it is to be understood that my invention may also be embodied in block form of teeth, that is, where the posterior and anterior molars are made in one piece as are also the premolars or bicuspids.

15 More specifically describing the lower denture A, the reference characters 1 designate the anterior molars, 2 the posterior molars, 3 the posterior bicuspid and 4 the anterior bicuspid. The occlusal surface of the anterior molar is composed of two substantially flat downwardly diverging inclined sides 5 and 6 which meet in a ridge 7 extending from front to rear of the tooth and substantially centrally thereof. The posterior and the anterior bicuspids 3 and 4 are similarly formed with ridges 8 and 9, and these ridges are in substantial alinement with the ridge 7 from front to rear of the denture and their sides are in substantially the same planes of the sides 5 and 6 of the ridge 7. The posterior molar 2 is somewhat different in form from the anterior molar 1 in that the occlusal surface thereof is composed of a substantially horizontal surface 10 which extends from substantially the plane of the ridge 7 toward the rear end of the denture, said surface being disposed at an angle to a surface 11 which is in substantially the plane of the surface 6 of the ridge 7. Another surface 12 meets the surface 10 and is in substantially the same plane as the surface 5 of the anterior molar. This formation provides an apex or point 13 at the anterior side of the molar 2 which is disposed in substantially the same plane and in alinement with the ridge 7.

Now coming to the upper denture B, the reference character 14 designates the anterior molar, 15 the posterior molar and 16 and 17 the posterior and anterior bicuspids, respectively. The anterior molar 14 has its occlusal surface composed of two inclined downwardly diverging surfaces 18 and 19 which are at substantially the same angle as the surfaces 5 and 6 of the anterior lower molar 1, but these surfaces meet in a substantially straight and horizontal portion 20 which substantially corresponds to the top of the ridge 7. Obviously the surfaces 18, 19 and 20 form a groove, and this groove extends from front to rear of the denture so as to receive the ridge 7. The posterior upper molar 15 is formed with a similar groove 21, but preferably the angle formed by the plane of the portion 20 with the plane 19 is slightly wider or more obtuse than that of the groove

in the anterior molar 14. The bicuspids 14 and 17 are formed with grooves 22 which are in substantial alinement from front to back of the jaw with the groove in the anterior molar and have their inclined sides in substantially the same planes as the sides 18 and 19 of the anterior molar. Each of the posterior molars 15 and the bicuspids 16 and 17 also have flat portions at the bases of the grooves corresponding to and in alinement with the surface 20 of the anterior molar.

With teeth so constructed and properly mounted in the upper and the lower plates it will be observed that the upper molars may freely slide relatively to the lower molar back and forth by contact of the inclined sides of the grooves and ridges, and free relative lateral movement of the dentures is possible by relative sliding of the surfaces of the ridges and the grooves. This action may be more easily understood from reference to Figure 4 of the drawings. The flat portion at the bases of the grooves in the upper molars also permit limited relative lateral movement of the dentures so that they may be comfortably adjusted to each other in occlusal position. In other words, there is no possibility of the upper molars and the lower molars interlocking with each other as is the case when the teeth conform to the natural formation of the occlusal surfaces where the cusps of the upper and lower teeth interlock with each other. With reference to Figure 4 it will be obvious that the grinding or cutting of food may take place by relative sliding action of the outer or buccal surfaces 6 of the ridges and the corresponding surface 18 of the grooves, and the mashing or crushing of the food after it has been so cut or shredded takes place between the lingual surface 5 of the ridge and the corresponding surface 14 of the groove in the upper denture.

To facilitate cutting, shredding and mastication of food, the buccal surfaces of the upper molars, for example the surface 18, are formed with saw-tooth shaped projections which have their pointed ends directed downwardly and between which are formed correspondingly shaped but reversed recesses 22. The buccal surfaces of the ridges of the lower molars, for example the surface 6, are formed with grooves 26 extending from front to rear that is, at substantially right angles to the projections 23. With this construction, it will be clear that the inclined edges 27 of the projections 23 will cooperate with the edges of the grooves 26 in cutting, tearing or shredding food, and the inclined sides of the projections 23 will direct the food into the bases of the grooves where the food will be caught between the lingual surfaces of the upper and lower teeth, for example the surfaces 5 and 19, and by them mashed and crushed. The grooves in the upper molars 14-17 may be of the same width, but pre-

erably the grooves gradually widen from the posterior molar 15 to the anterior bicuspid 17, as clearly shown in Figure 6 of the drawing. This is to accommodate the somewhat greater lateral movement of the jaws toward the forward points thereof as contrasted with the movements at the pivotal points.

The obtuse angle of the grooves in the upper posterior molars 15 prevent contact of the posterior molars at all but one or the other lingual side during chewing or food-grinding action of the jaws. In this connection, it should be noted that the obtuseness results in cutting away the rear buccal cusp of the tooth, and the horizontal plane of the surface 10 cuts away the corresponding portion of the lower posterior molar so that upon closing of the jaws and lateral movement thereof there is no contact between the upper and lower molars which might cause tilting or lateral displacement of the plates. Furthermore, the particular formation of the upper or occlusal surface of the posterior lower molars admits of the tooth being moved forwardly or rearwardly and the apex may enter the groove of the anterior upper molar if necessary, to meet different conditions.

Further, it will be noted that the inside or lingual cusps of the lower molars are cut away entirely and that the outside or buccal cusps are cut away on an inwardly and upwardly inclined plane so that there is no possibility of the tongue getting beneath projections on the lower teeth and lifting the plate.

35 While I have shown the now preferred embodiment of my invention, it will be understood that this is primarily for the purpose of illustrating the principles of the invention and that many modifications and changes 40 may be made in the details of construction of the contours of artificial teeth without departing from the spirit or scope of the invention. Therefore, I do not desire to be understood as limiting myself except as required 45 by the following claims when construed in the light of the prior art.

Having thus described the invention, what I claim is:

1. In dentures, a lower set of molar teeth 50 having their occlusal surfaces in the form of ridges extending in front to rear direction and having downwardly receding oppositely inclined surfaces, and an upper set of molars having their occlusal surfaces in the form of 55 grooves substantially corresponding in cross-sectional shape to said ridges and extending in the same direction, said ridges entering said grooves when the upper and lower teeth are in occlusal position and permitting free relative sliding of the upper and lower teeth back and forth and laterally, one side of said 60 grooves having projections to cooperate with said ridges in cutting, shredding or tearing food.

65 2. In dentures, a lower set of molar teeth

having their occlusal surfaces in the form of ridges extending in front to rear direction and having downwardly receding oppositely inclined surfaces, and an upper set of molars having their occlusal surfaces in the form of 70 grooves substantially corresponding in cross-sectional shape to said ridges and extending in the same direction, said ridges entering said grooves when the upper and lower teeth are in occlusal position and permitting free 75 relative sliding of the upper and lower teeth back and forth and laterally, one of said grooves and the corresponding side of said ridges having cooperating projections and recesses the edges of which upon contact due 80 to masticating movement of the jaws serve to cut, shred or tear food.

3. In dentures, a lower set of molar teeth having their occlusal surfaces in the form of ridges extending in front to rear direction 85 and having downwardly receding oppositely inclined surfaces, and an upper set of molars having their occlusal surfaces in the form of grooves substantially corresponding in cross-sectional shape to said ridges and extending 90 in the same direction, said ridges entering said grooves when the upper and lower teeth are in occlusal position and permitting free relative sliding of the upper and lower teeth back and forth and laterally, one side of said 95 grooves having saw-tooth shaped projections with the points directed downwardly and recesses between them to cooperate with said ridges in cutting, shredding or tearing food.

4. In dentures, an upper set of molars having their masticating surfaces in the form of grooves extending from front to rear and having oppositely inclined sides downwardly diverging and from a substantially flat horizontal bottom portion, and a lower set of 105 molars having their masticating surfaces in the form of ridges having oppositely inclined and downwardly diverging sides corresponding to said grooves, said ridges entering said grooves when the upper and lower teeth are in occlusal position and permitting free relative sliding of the upper and lower teeth back and forth and laterally, and said flat bottoms of said grooves providing a limited amount of lateral play or movement of the dentures 110 without vertical movement.

5. In dentures, a lower set of molar teeth having their occlusal surfaces in the form of ridges extending in front to rear direction and having downwardly receding oppositely 120 inclined surfaces, and an upper set of molars having their occlusal surfaces in the form of grooves substantially corresponding in cross-sectional shape to said ridges and extending in the same direction, said ridges entering 125 said grooves when the upper and lower teeth are in occlusal position and permitting free relative sliding of the upper and lower teeth back and forth and laterally, said grooves gradually increasing in width from the rear to 130

the front to compensate for differences in the extent of natural lateral movement of the jaws forwardly from the pivotal point.

6. In dentures, a lower set of molar teeth having their occlusal surfaces in the form of ridges extending in front to rear direction and having downwardly receding oppositely inclined surfaces, and an upper set of molars having their occlusal surfaces in the form of grooves substantially corresponding in cross-sectional shape to said ridges and extending in the same direction, said ridges entering said grooves when the upper and lower teeth are in occlusal position and permitting free relative sliding of the upper and lower teeth back and forth and laterally, the groove in the posterior upper molar being more obtuse than the grooves in the other upper teeth to prevent contact between them in all but one position, to obviate tilting or lateral displacement of the dentures.

7. In dentures, a lower set of molar teeth having their occlusal surfaces in the form of ridges extending in front to rear direction and having downwardly receding oppositely inclined surfaces, and an upper set of molars having their occlusal surfaces in the form of grooves substantially corresponding in cross-sectional shape to said ridges and extending in the same direction, said ridges entering said grooves when the upper and lower teeth are in occlusal position and permitting free relative sliding of the upper and lower teeth back and forth and laterally, the posterior lower molar having the rear of its occlusal surface rearwardly receding in a substantially horizontal plane.

8. In dentures, a lower set of molar teeth, each tooth having on its masticating surface a single ridge having downwardly receding oppositely inclined sides which meet the respective buccal and lingual sides of the teeth and are in substantial alinement from front to rear of the jaw with the ridges of adjacent teeth, and an upper set of teeth, each tooth having a single groove with inclined sides in

alinement from front to rear of the jaw with the grooves of adjacent teeth to embrace said ridges of the teeth on the lower jaw when the upper set and the lower set of teeth are in occlusal position, whereby said upper set and said lower set may relatively freely slide from front to back and laterally. 50

9. In dentures, a lower set of molar teeth, each tooth having on its masticating surface a single ridge having downwardly receding oppositely inclined sides which meet the respective buccal and lingual sides of the teeth and are in substantial alinement from front to rear of the jaw with the ridges of adjacent teeth, and an upper set of teeth, each tooth having a single groove, formed with a flat horizontal bottom and flat sides diverging downwardly from said bottom and in alinement from front to rear of the jaw with the grooves of adjacent teeth to embrace said ridges of the teeth on the lower jaw when the upper and lower set of teeth are in occlusal position, whereby said upper set and said lower set may relatively freely slide from front to back and laterally. 55

10. An artificial molar tooth having its occlusal surface composed of two converging flat sides which meet in a ridge on the longitudinal center line of the tooth and extend respectively from the lingual and the buccal sides of the tooth. 70

11. An artificial molar tooth having on its occlusal surface a single longitudinal groove formed of two flat sides converging respectively from the lingual and the buccal sides of the tooth toward the longitudinal center thereof, one of said sides having a plurality of projections providing cutting edges transverse of the plane of said side. 75

12. The artificial tooth set forth in claim 11 wherein said cutting edges are inclined to the longitudinal center line of the tooth and extend from the edges of the tooth to the bottom of said groove. 80
